UNITED STATES PATENT OFFICE.

ALBERT DU BRUL, DECEASED, LATE OF FORT THOMAS, KENTUCKY, BY FRANCES GOSELIN DU BRUL, EXECUTRIX, OF FORT THOMAS, KENTUCKY, ASSIGNOR TO THE MILLER, DU BRUL & PETERS MFG. CO., OF CINCINNATI, OHIO, A CORPORATION OF OHIO.

PAPER-REEL BRAKE

1,242,927.

Specification of Letters Patent. Patented Oct. 16, 1917.

Original application filed December 17, 1913, Serial No. 807,256. Divided and this application filed August 22, 1916. Serial No. 116,354.

To all whom it may concern:

Be it known that ALBERT DU BRUL, deceased, late a citizen of the United States, and resident of Fort Thomas, in the county 5 of Campbell and State of Kentucky, did invent certain new and useful Improvements in Paper-Reel Brakes, of which the following is a specification.

This application is a division of an application 10 filed December 17th, 1913, Serial No. 807,256, for Letters Patent for improvements in cigarette machines, in which the subject matter of the present application was embodied by way of illustrating one 15 use for which it might be advantageously employed.

The invention relates to a device to be applied to a reel of paper or other material that is to be fed continuously to a machine 20 that consumes the material in the production of goods or articles, and the invention has for its object to provide a simple and effective means that will absorb the excessive tensile stresses due to sudden starting of the 25 machine or sudden changes in its speed, and which will also develop and automatically maintain a delicately measured braking effect upon the reel, so long as the reel is running and notwithstanding reduction in 30 the diameter of the reel due to the consumption of the material.

When a machine uses paper from a reel at a rate of speed which necessitates a rapid paying-out of the paper strip or web, and 35 particularly when the paper is comparatively thin, starting of the machine tends to snap the paper, and this tendency is aggravated if the reel over-runs or races at the previous stopping, in a manner to pay 40 out considerable slack paper, the reason for this being that the machine accelerates quickly while the slack is being taken up, and the entire inertia of the stationary reel must be overcome by tension exerted 45 through the paper in getting the reel started. If a friction brake be applied to the surface of the reel, it increases the resistance of the reel to starting and aggravates the trouble. If the brake resistance is reduced to decrease 50 the danger of breaking the paper, then there is some slight over-running of the reel with consequent slack that augments the danger of breaking, and even if the braking pressure

be delicately adjusted to run with comparative safety when the reel is full and of comparatively large diameter, the brake resistance is too great when the diameter of the reel is reduced by consumption of the paper, and the inherent resistance to rotation of the reel has to be overcome through the 60 leverage of the smaller diameter.

The present invention overcomes the several difficulties above suggested, primarily by providing the paper-reel brake embodying two main characteristics, namely, accurate adjustability to precisely the resistance desired, and automatic regulation of resistance, with variation in the diameter of the reel. But while with these characteristics the advantages of the invention may be 70 realized to a highly important degree, a further characteristic is preferably embodied in order that the advantages may be realized to the fullest measure, which consists in an automatic slack take-up that imposes tension upon the paper at times of starting in the taking up of the slack, and starts the paper reel gradually and without danger of breaking the paper.

For purposes of illustration, an embodiment of the invention in form suitable for controlling the paper feed of a continuous cigarette machine, is shown and described in the present application, but it is to be understood that the invention is not limited to 85 this particular use, but is applicable to paper fed from reels in other types of industrial machinery, such for instance as feeding a thin strip or web of paper to be twisted or spun in making cord, feeding paper 90 to be wound into a reel of ribbon to serve as a separating body for the coils of ribbon, delicate threads fed from a spool or bobbin, etc.

In the accompanying drawing—

Figure 1 is a side elevation of a paper reel, suitably mounted for paying out to a paper-consuming machine, and having the preferred embodiment of the invention associated therewith; and

Fig. 2 is a top plan view of a braking device detached.

1 represents a paper reel of standard type, rotatably secured by some convenient means, such as wing nut 2, upon a spindle 3 carried by a suitable support 4.

In machines which draw paper from such a reel at a comparatively rapid rate, as for instance in high speed continuous cigarette machines, and particularly where the pull of the machine upon the paper is rendered somewhat irregular by variations in the resistance to the manufactured article passing through the machine, a reel will feed quite irregularly, first speeding up and then hanging back, so that excessive tension is imposed at intervals upon the paper, which frequently breaks the paper and entails a considerable loss in the production of the machine, particularly where the paper has to be threaded through a more or less circuitous passage, to re-introduce it into the machine. To overcome this effect, a brake lever 5, fulcrumed at 6, provided with a shoe 7, bears upon the periphery of the reel and develops friction to such a degree as will prevent racing of the reel so long as the paper is being fed, even though the pull upon the paper may be irregular. Different papers vary greatly in the co-efficient of friction that will be developed by the brake shoe 7 with a given pressure imposed through the medium of the lever 5, and this variation in friction may be different in the same paper under different atmospheric conditions. In order to be able to adjust with exactness the frictional resistance imposed through the shoe 7, lever 5 is provided with a weight 8 that is adjustable thereon in a manner to increase or decrease at will, the pressure imposed through the lever. This weight is conveniently rendered adjustable by means of a clamping strap 9 surrounding the hub or fulcrum-bearing 10 of the lever 5, so that it may be fixed at any desired angle relatively to the lever. Being offset from its center of adjustment, which is the fulcrum 6 by means of its arm 11, such adjustment may be graduated with exactness.

A further advantage of the described form of adjustment for the weight 8 is that it automatically graduates pressure exerted through the lever 5 as the reel 1 grows smaller with the unwinding of paper therefrom. That is to say, as the lever 5 descends and the weight 8 with its arm 11 rises from the position shown in Fig. 1, the horizontal distance or leverage through which the weight acts upon the lever 5 will increase, and its counterbalancing effect upon the lever 5 will correspondingly increase, so that as the diameter of the reel grows less and the inherent resistance to rotation is being overcome through a constantly smaller radius of the reel, the braking resistance is correspondingly relieved and the tension on the paper approaches constancy.

The arm 11 may be adjusted to a position toward the left hand of Fig. 1 beyond the perpendicular, whereupon it will add to the

braking pressure of the lever 5, and this may be necessary when the surface of the paper to be controlled is exceptionally smooth. But this does not change the principle of operation, for it is obvious that when in a position to add its weight to that of the lever 5, descent of the lever 5 will tend to throw the counter-weight 8 farther away from the horizontal and toward the perpendicular, so that the braking effect will be gradually reduced as the diameter of the reel reduces, just as in the instance first described.

In controlling the paper supplied to cigarette machines and other machines employing comparatively thin paper, it will often be desirable to regulate the pressure of the shoe 7 so that there will be a slight slackening of the paper when the machine is stopped. In order to take up this slack and transmit gradually to the reel, the pull incident to starting the machine again, an auxiliary brake lever 12 is pivoted at 13 to the lever 5 and provided with a brake shoe 14 through which it rests preferably by gravity alone, upon the portion of the paper web or strip extending away from the reel toward the consuming machine. This auxiliary lever takes up any slack in the web, as suggested by the dotted line position in which it is shown in Fig. 1, so that as soon as the pull is exerted of sufficient force to straighten the paper, lifting the weight of the auxiliary lever 12 will impose sufficient resistance to start revolution of the reel gradually.

What is claimed is:—

1. In a material unwinding machine, a braking lever fulcrumed to act by gravity on the periphery of a reel of paper, and an auxiliary tension means mounted on said braking lever and free to act by gravity to materially deflect the web of paper after it leaves said reel, but yielding to permit straightening of the web, under tension on the web.

2. In a material unwinding machine, a braking lever adapted to act on the periphery of a reel of paper, and an auxiliary tension means mounted on said braking lever and extending beyond the same to act by gravity on the web of paper after it leaves said reel, deflecting said web of paper but yielding to permit it to straighten under abnormal tension, and an adjustable weight controlling the braking action of said braking lever against the reel of paper.

3. In a material unwinding machine, a paper tensioning device comprising a fulcrumed brake lever, an adjustable balance weight attached to said lever, and an auxiliary tension bar pivotally mounted on the braking end of said lever, and extending beyond the same in position to deflect the paper extending from the reel.

4. A combined constant braking and take-up device for material fed from reels, comprising an auxiliary brake lever yieldingly bearing against the material and adapted to take up slack therein at a point beyond the reel, and a braking lever, upon which said auxiliary lever is mounted, adapted to bear constantly upon the reel of material, independently of the take-up action of the auxiliary lever.

5. A combined constant braking and take-up device for material fed from reels, comprising an auxiliary brake lever yieldingly bearing against the material and adapted

to take up slack therein at a point beyond the reel, and a braking lever, upon which said auxiliary lever is mounted, adapted to bear constantly upon the reel of material, independently of the take-up action of the auxiliary lever; said auxiliary lever being pivoted to the braking lever, at a point adjacent to the braking contact with the reel.

The foregoing specification signed at Cincinnati, Ohio, this 11th day of August, 1916.
